UNITED STATES PATENT OFFICE.

JESSE C. OWENS, OF LOS ANGELES, CALIFORNIA.

TOILET TANK.

Application filed September 16, 1924. Serial No. 737,994.

To all whom it may concern:

Be it known that I, JESSE C. OWENS, a citizen of the United States, residing at Los Angeles, in the county of Los Angeles and State of California, have invented new and useful Improvements in Toilet Tanks, of which the following is a specification.

This invention relates to a flush tank for use with closets and the like, wherein a large volume of water is accumulated in a closed receptacle preparatory to discharge, the rate of accumulation being less than that of discharge, and the receptacle acting as a pneumatic tank. The primary object of this invention is to provide a closed tank wherein the water is initially forced out of the tank by the pneumatic pressure of entrapped air. Another object of this invention is to provide a tank so arranged that the delivery of water thereto in charging it is noiseless. A further object of this invention is to provide a tank wherein the valves and movable parts are built into a unit easily installed in the receptacle and easily removed therefrom.

These objects together with other objects and corresponding accomplishments are obtained by means of the embodiment of my invention illustrated in the accompanying drawings, in which:

Fig. 1 is a side elevation of a tank mounted upon a wall and connected to a closet, a fragment of the latter being shown; Fig. 2 is a section as seen on the line 2—2 of Fig. 1; Fig. 3 is an enlarged section of the discharge mechanism; and Fig. 4 is a section as seen on the line 4—4 of Fig. 2 on an enlarged scale.

Referring more particularly to the drawing, 5 indicates a flat wall tank comprising a closed receptacle having a hole at the top for the insertion of the tank mechanism. Disposed within the tank are ribs 6 extending across the tank, secured to the walls thereof and serving the purpose of strengthening members to aid the tank walls in withstanding pressure. The ribs 6 are perforated to permit water to freely circulate. A cap 7 is arranged to rest upon the upper portion of the tank and cover parts projecting above the top of the tank proper.

A cover 8 is provided for closing the opening in the top of the tank, and mounted therein is a tubular casing 9 which extends above the cover 8 and is arranged to be connected by a suitable fitting 10 with a dry air pipe 11. The casing 9 has a valve port on its lower side adapted to be closed by an air valve 12. Extending from the casing above the valve 12 is a branch 13 adapted to have a bypass tube 14 connected therewith. Valve 12 has a stem 15 mounted in a guide within the casing 9 and projecting below the valve. Mounted upon the stem 15 is a float ball 16. The parts are so arranged that as a charge of water fills the receptacle, the level of the water rising, float 16 will be raised finally closing valve 12 and thereby shutting off communication between the air inlet pipe 11 and the tank.

Mounted in an opening in the tank at the bottom is a valve casing 17 having a branch 18 extending laterally therefrom and connected to bypass pipe 14. A seat 19 is formed about the port at the upper part of the valve casing, and cooperating therewith is a valve disc 20. At the center of the valve disc is a tube 21 forming a relief port. The upper end thereof serves as a seat for the relief valve 22. Relief valve 22 is mounted upon a stem 23 having abutment nuts 24 threaded thereon and arranged to abut the tube in valve disc 20 after relief valve 22 has been raised from its seat. Bridges 25 and 26 having openings through which stem 23 slidably extends serve as guides for the valve stem. The stem is provided with an annular recess 27 arranged to be engaged by a lock member later described. The casing 17 is connected by a flush pipe 28 to the bowl. Pivotally mounted in a casing 17 is a lever 29 having a forked end arranged to embrace the valve stem 23 below the abutment nuts. Branch 13 of air valve casing 9 is tubular and open at the top. It is provided with a bracket 30 in which is guided a push rod 31 resting in a socket in the end of lever 29. The top of the push rod is provided with a follower head 32 for engagement by a cam. A compression spring 33 is disposed about the push rod and is interposed between the bracket

95
100

30 and the follower. The cap 7 is provided with a bearing 34 supporting a shaft 35 having at one end thereof a cam 36 and at the other end outside of the cap a handle 37. 5 Spring 33 tends to hold the push rod in its upper position so that lever 29 exerts no upward pressure upon the valve stem 23 and valve disc 20 is seated. This condition prevails when the cam 36 is in the position 10 shown in Figs. 2 and 4.

There are two high spots on the cam so that when the shaft 35 is turned through 90° from the position shown in Fig. 2 the push rod will be moved downward causing 15 the lever 29 to be turned, thereby raising stem 23. The initial movement of stem 23 lifts the relief valve 22 so that water may enter through the valve disc and equalize the pressure on both sides of valve disc 20. 20 Further movement of the push rod causes the stem to be still further raised, nut 24 engaging the tube 21 and raising disc 20 from its seat.

In order to hold the discharge valve 20 in 25 open position during the discharge of the contents of the tank, a lock cup 38 is provided. This cup is loosely mounted upon the valve stem 23 so that it may tilt and is provided with an internal lip 39. Upon 30 the water rushing through the discharge casing 17, it will engage the cup 38. The side of the cup opposite to lip 39 is disposed at a greater angle than the opposite side so that the cup will be tilted by the impact of 35 the stream of water and lip 39 will enter recess 27 on the stem, locking the stem. The cup will be maintained in this position during the discharge of the water thereby 40 holding the stem and the valve disc in its open position upon the flow of water stopping, the impact on the cup ceases and the latter rights itself.

At one side of the tank and in the bottom thereof is a water inlet nipple 40. This 45 nipple is arranged to be connected to a source of water supply such as the house service pipes. Mounted upon the nipple within the tank is a hood 41 of conical form serving as a nozzle and having secured to the apex thereof a refill tube 42. In the 50 sides of the hood are ports 43 connecting directly with the lower portion of the tank. The refill tube is bent toward the air valve and ends in a nozzle which will direct a stream of water toward the air valve and 55 into the air port when the latter is open. If the tank is empty and valve 20 is seated the water will enter the tank through the water inlet 40, passing out through the ports 60 43 in the hood and some moving upwardly through the refill tube and being projected through the air port into the branch 13 and thence by way of the bypass tube 14 to the branch 18 and through the closet connection 65 to the bowl.

Assume that the tank is full of water as shown in Fig. 2 and that the members are in the positions shown. The tank is closed so that air is entrapped at the top and the pneumatic pressure is equal to the pressure 70 in the house service system. No water will enter the flush tank from the house service system due to the equalization of pressure. To flush the tank, handle 37 is turned, thereby moving push rod 31 downward, swinging 75 lever 29 and lifting valve stem 23 so as to raise valve disc 20. The out-rushing water engages the lock cup tilting the latter to locking position and maintaining the discharge valve in open position until all the 80 water has been discharged. As soon as the water in the tank is lowered sufficiently float 16 moves downwardly opening air valve 12. This permits air to enter the top of the tank and thereafter the tank discharges by gravity. When all of the water has been 85 discharged from the tank and when valve 20 closes, water begins to accumulate in the tank entering from water inlet 40, air passing out through the air port 9. Some of 90 the water is projected through the refill tube 42, through the air port and by way of the bypass tube 14 and branch 18 into the discharge. As the water rises in the tank 95 it lifts the float 16, and raises the latter so as to close the air valve 12. Thereafter the filling of the tank is performed against the pneumatic pressure of the entrapped air. Water ceases to enter when the pressure within the tank is equal to the pressure in 100 the house service system.

What I claim is:

1. A flush tank comprising the combination of a closed receptacle having a discharge port at the bottom, a lift valve therefor, means for opening and for holding said valve open during the outflow of the water contained in said receptacle, an air port at the top of said receptacle, an air valve therefor, float means connected to said air valve for closing the latter at a predetermined upper level, a bypass connecting said air port beyond said air valve and said discharge port beyond said lift valve, a water inlet at the bottom of said receptacle freely connected to a source of water supply under pressure, and a refill tube extending from said inlet for directing water into said air port and thereby through said bypass and into said discharge port. 115

2. A flush tank comprising the combination of a closed receptacle having a discharge port at the bottom, a lift valve therefor, means for opening said valve, means for holding said valve open during the outflow of the water contained in said receptacle, an air port at the top of said receptacle, an air valve therefor, float means connected to said air valve for closing the latter at a predetermined upper level, a bypass connecting 130

said air port beyond said air valve and said discharge port beyond said lift valve, a water inlet at the bottom of said receptacle for delivering water thereto freely connected to a source of water supply under pressure, a hood over said inlet having lateral ports and a nozzle, a refill tube extending

from said nozzle for directing water into said air port and thereby through said bypass into said discharge port. ¹⁰

In witness that I claim the foregoing I have hereunto subscribed my name this 4th day of September, 1924.

JESSE C. OWENS.
